UNITED STATES PATENT OFFICE

JOHN W. McELHINNY, OF CHICAGO, ILLINOIS, ASSIGNOR OF ONE-HALF TO WILLIAM M. ROBERTS, OF OAK PARK, ILLINOIS.

TABLE.

1,324,259.

Specification of Letters Patent.

Patented Dec. 9, 1919.

Application filed November 23, 1917. Serial No. 203,504.

To all whom it may concern:

Be it known that I, JOHN W. McELHINNY, a citizen of the United States, residing at Chicago, in the county of Cook and State of Illinois, have invented certain new and useful Improvements in Tables, of which the following is a description.

My invention belongs to that general class of devices known as tables and particularly to a combined folding table and kit carrier for use by paper hangers, decorators and the like, but it may of course be used by mechanics engaged in other trades in which it may be found applicable. The invention has among its objects the production of a device of the kind described that is simple, convenient, compact, rigid, durable, attractive and satisfactory. It has particularly among its objects the production of an extremely rigid and convenient table of the desired size and height that may be folded in a small space for convenience in transporting and at the same time serve as a satisfactory carrier for the mechanic's tools or kit or portion thereof. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Figure 1 is a perspective view of the device partially folded;

Fig. 2 is a sectional view taken substantially on line 2—2 of Fig. 3;

Fig. 3 is a top plan view of the table open with the extensions arranged at the ends;

Fig. 4 is a side elevation of a portion of the same;

Fig. 5 is a sectional view taken substantially on line 5—5 of Fig. 2, the legs partially folded;

Fig. 6 is a sectional view taken substantially on line 6—6 of Fig. 3;

Fig. 7 is a sectional view taken substantially on line 7—7 of Fig. 6;

Fig. 8 is a sectional view taken substantially on line 8—8 of Fig. 3 with the extensions in place; and

Fig. 9 is a perspective view of one of the extensions 39.

Referring to the drawings, the table consists of the top parts 1 and 2 which are preferably provided with sides or flanges at the sides 3 and ends at 4 and 5. The two parts are pivotally secured together at the ends 4—4 by means of hinges 6 or equivalent means for the purpose. At the opposite or free ends of the table parts 1 provide co-operating locking means 8—9 or the equivalent for the purpose for retaining the top parts folded and on one side 3, I provide a hand 10, by means of which the table may be conveniently and comfortably carried when folded.

The table is provided with a pair of legs 11—11 for each top part, the same being preferably secured together and braced by means of the cross bars 12 and 13, 14—14, etc., being reinforcing plates which may be employed if desired. The leg parts 11 are made substantially of a length to fit in the top parts between the ends 4 and 5, and of a width or depth not to project beyond the sides 3. However, I prefer not to attach the legs 11 directly to the top, as to do so, in order to have the top face of the table the desired distance from the floor, the table top parts would have to be of a length greater than is ordinarily desired by the paper hanger and greater than would be convenient in transporting the device. I therefore hinge or pivotally secure the leg parts 11 to the table parts by means of extensions or links 15, which are pivotally secured at 16 to the legs at their upper ends and at 17 to brackets carried on the table top parts as shown secured to the sides 3. The parts 11 and 15 form substantially folding legs which may be folded against the top parts.

In order, however, to limit the movement of the parts in opening and setting up the legs to operative position and make the legs rigid, I provide plates 19 on the ends of the legs having stops 20 formed to engage the links and limit the pivotal movement of the parts about the points 16. Any equivalent construction may be employed, but that shown is simple and has been found to be particularly satisfactory. To brace the legs and maintain them in open supporting positions and prevent a pivotal movement about the points 17, I provide brace members 21—22. As shown, members 21 are pivotally secured

at 23 to the legs 11, and members 22 pivotally secured at 24 to the sides 3, the two members or legs at each side being pivotally secured together at 25, a stop 26, however, 5 limiting the pivotal movement. In Fig. 4 the legs at one end of the table are shown in folded position by the full lines and partially folded by the dotted lines, while in Fig. 1 on one side they are shown completely 10 folded and on the opposite sides partially folded.

Sometimes the paper hanger desires a table longer or wider than that afforded by the two top parts 1 and 2. To meet this 15 requirement I provide the extension top parts 28, the same being arranged to be positioned at the ends or at the sides of the table. In Fig. 3 they are shown by the full lines at the ends of the table and by the 20 dotted lines at the sides of the table. Referring particularly to Figs. 1, 3 and 6, the extension parts 28 are provided with the cleats 29, which tend to stiffen the parts and which are extended as at 30 to form supporting members which may be inserted in 25 holes or openings 31 in the sides or free ends of the table top parts. To secure the extension parts in the table when closed, as well as to carry them when not desired for 30 use when the table is open, I arrange the same so that each extension part is carried on one pair of legs. Referring particularly to Figs. 6 and 7, the connecting bars or braces 12 and 13 are arranged at an angle 35 to each other and the adjacent edges beveled as shown at 32 in Fig. 7. The cleats 29 are also beveled as at 33 and arranged so that they are engaged with the braces 12 and 13 when the extension part 28 is positioned 40 substantially as shown in the figures. If, however, part 28 is moved in the direction indicated by the arrow in Fig. 6, the cleats 29 will become disengaged from the cleats or braces 12 and 13 so the extension part 45 may be readily moved and positioned as desired.

Where the extension parts are arranged at the side of the table as shown in the dotted lines in Fig. 3 and it is desired to 50 bridge over the space between the extensions, an extension 35 is provided. This is ordinarily maintained in place on one of the top parts by the cleat 36 and the button 37 or equivalent means for the purpose. In 55 order that the extension part 35 may be flush with the extensions 28, I prefer to form a shoulder 38 on the extensions 28, upon which the extension 35 may rest. In case it is not desired to provide extensions 60 similar to 28 for use at both the sides and ends at the same time, I provide the extensions 39, shown most clearly in Figs. 6 and 9, which may be fitted into the holes or openings 31 and serve as extensions. While they 65 are not always necessary, I have found that

frequently they are very desirable, even though not essential. They may be maintained in place by the clips 40 arranged on cleats 29 or in an equivalent manner. In addition to the extension parts various other 70 tools and implements, as for example, brush 42, straight edge 43, etc., may be carried in the table when folded. I have not considered it necessary, however, to illustrate or to describe the various tools which may be 75 so arranged.

In using the table, the same may be transported to where desired when folded, and after reaching the place at which the work is to be done, the free ends of the top 80 parts may be released and the table opened up, the legs being pulled down substantially as indicated in Figs. 2 and 4 as well as Fig. 6. The extension parts may be positioned if desired. The table may then be used like 85 any ordinary table and when the work is completed, the table folded with the parts and tools arranged therein and the same carried away. The table is of extremely light weight and very compact, and while the 90 table parts are comparatively short as compared with the height of the table from the floor, yet the legs may be entirely folded within the top parts allowing ample room on the inside for the tools and implements. The device is particularly intended for and found most convenient for use in cities where travel on street cars or similar conveyance is frequently required. In some cases it is not permitted to take a board on 95 a car greater than six feet in length, while it is ordinarily desired to use at least a seven foot board or longer. My device fulfills all of the requirements of the paper hanger, and in addition he does not have 100 to carry about board supports, or as they are termed "horses," which are usually cumbersome to carry. In fact with my device, he ordinarily does not have to carry a grip or suit case for his tools and clothes in addition to the table.

Having thus described my invention, it is obvious that various immaterial modifications may be made in the same without departing from the spirit of my invention, 115 hence I do not wish to be understood as limiting myself to the exact form, construction, arrangement and combination of parts herein shown and described or uses mentioned.

What I claim as new and desire to secure 120 by Letters Patent is:—

1. In a table of the kind described and in combination, a top consisting of a plurality of parts arranged end to end and hinged together at the meeting ends, a pair of legs 125 arranged at the free end of each part, the legs being adapted to be folded on the top and when the legs are in supporting position, the distance from the table top to the free ends of the legs being greater than the 130

length of the top part, each leg comprising a main rigid leg section and a short upper extension pivotally secured at one end to the upper end of the main leg section, and at its upper end to a part of the table top, the main leg sections constituting the greater part of the legs and being of a length less than the length of the table part, said main leg sections extending vertically when in supporting position.

2. In a table of the kind described and in combination, a top consisting of a plurality of parts arranged end to end and hinged together at the meeting ends, a pair of legs arranged at the free end of each part, the legs being adapted to be folded on the top and when the legs are in supporting position, the distance from the table top to the free ends of the legs being greater than the length of the top part, each leg comprising a main rigid leg section and a short upper extension pivotally secured at one end to the upper end of the main leg section, and at its upper end to a part of the table top, the main leg sections constituting the greater part of the legs and being of a length less than the length of the table top, said main leg sections extending vertically when in supporting position, and means carried by the top parts and slidably engaging the rigid main leg sections for maintaining the same in vertical supporting position.

3. In a table of the kind described and in combination, a top consisting of a plurality of parts arranged end to end and hinged together at the meeting ends, a pair of legs arranged at the free end of each part, the legs being adapted to be folded on the top and when the legs are in supporting position, the distance from the table top to the free ends of the legs being greater than the length of the top part, each leg comprising a main rigid leg section and a short upper extension pivotally secured at one end to the upper end of the main leg section, and at its upper end to a part of the table top, the main leg sections constituting the greater part of the legs and being of a length less than the length of the table part, said main leg sections extending vertically when in supporting position, and means on the upper ends of the main leg sections to limit the unfolding movement of the main leg sections relatively to their upper extensions.

4. In a table of the kind described and in combination, a top consisting of two parts arranged end to end and hinged together thereat, a pair of legs arranged at the free end of each top part, cross bars connecting the legs of each pair, and detachable top part extensions, said extensions provided with means for detachably securing the same to the cross bars of the legs.

5. In a table of the kind described and in combination, a top consisting of two parts arranged end to end and hinged together thereat, a pair of legs arranged at the free end of each top part, cross bars connecting the legs of each pair, means for securing the legs to the top parts at points spaced from the free ends of the top parts whereby the legs may be folded against the top parts on the under side thereof, and detachable top part extensions, said extensions provided with means for detachably securing the same to the cross bars of the legs.

6. In a table of the kind described and in combination, a top consisting of two parts arranged end to end and hinged together thereat, a pair of legs arranged at the free end of each top part, spaced cross bars connecting the legs of each bar, a detachable top part extension, and means on said extension and the cross bars of one of the pairs of legs for detachably securing said extension to said cross bars.

7. In a table of the kind described and in combination, a top consisting of two parts arranged end to end and hinged together thereat, a pair of legs arranged at the free end of each top part, spaced cross bars connecting the legs of each pair, said cross bars being arranged to extend at an angle to each other and being provided with beveled faces, detachable top part extensions, said extensions being provided with beveled faces, the detachable top part extensions being adapted to be detachably held between the cross bars of the pairs of legs, the beveled faces of the top part extensions coöoperating with the beveled faces of the cross bars.

In testimony whereof, I have hereunto signed my name in the presence of two subscribing witnesses.

JOHN W. McELHINNY.
